ELECTRICAL CONNECTION MEANS

Harry A. Douglas, Bronson, Mich.

Application July 8, 1935, Serial No. 30,278

12 Claims. (Cl. 173—357)

My invention relates to electrical connection means, such as may be embodied in means for receiving plug connections and more particularly for receiving electrical incandescent lamps. In 5 its more specific aspects my invention relates to means for adapting plug connections or incandescent lamps for use in socket means larger than the plug connections or lamps. The principal object of my invention is to provide new and improved electrical connection means of these types. In the drawing accompanying this specification, and forming a part of this application, I have shown, for purposes of illustration, one form which my invention may assume. In the drawing:

Figure 1 is a longitudinal section of one embodiment of my invention,

Figure 2 is a section taken on the line 2—2 of Figure 1, looking in the direction of the arrows, with the lamp removed, and

Figure 3 is a perspective view of the parts shown in Figure 1, disassembled, the lamp being fragmentarily shown.

In the embodiment illustrated in the drawing 25 the connection means comprises a metallic socket shell 10 here shown as of cylindrical form, provided with an integral annular flange 11 which may serve as an abutment in mounting the shell. The shell may be mounted and/or electrically connected in any suitable manner (not shown).

Disposed slidably within the shell 10 is an insulating disc 12 having a central aperture 13 through which the metallic stripped end portion 14 of an insulated conductor 15 is disposed. The end 16 of the insulation of the conductor 30 15 is here shown as abutting one face of the insulating disc 12, and the end of the metallic portion 14 of the conductor is shown as spread over the other side of the disc and covered with

40 solder to form a contact 17. The right hand end of the shell 10, as viewed in Figure 1, is open, but has its margin turned radially inwardly to serve as an abutment 18 for an insulating disc 19 having a central aperture 20 through which the insulated conductor 15 freely passes. Surrounding the conductor 15 and disposed within the shell 10 between the insulating discs 12, 19 45 is a helical spring 21 which biases the insulating disc 19 toward the right and the insulated disc 12 toward the left.

50 An adapter 22, here shown as in the form of a generally cylindrical plug, fitting slidably within the shell 10, comprises a comparatively heavy cylindrical portion 23 provided with a concentric cylindrical aperture 24 adapted to receive

another plug, in this instance a base 25 of an incandescent electric lamp 26. At the right hand end, as viewed in Figure 1, the cylindrical aperture 24 is counter-sunk by a larger cylindrical aperture 27, in turn counter-sunk by a still larger cylindrical aperture 28 forming a shoulder 29 in abutment with which is an insulating disc 30. The insulating disc 30 is held in abutment with the shoulder 29 by turning the margin 31 of the right hand end of the adapter 22 radially inwardly against the right hand face of the insulating disc 30. The insulating disc 30 is provided with a central aperture 32 through which a generally cylindrical conducting member 33 is slidably disposed. The right hand end of the conducting member 33 is flared outwardly somewhat to form a flange 34 sufficiently large to prevent the conducting member 33 from passing through the aperture 32 in the insulating disc 30. The left hand end of the conducting member 33 is provided with a somewhat larger frustro-conical outwardly flaring flange 35, which also prevents the conducting member 33 from passing through the aperture 32 in the insulating disc 30. The end 20 of the conducting member 33, having the flange 25 34, is adapted to engage the contact 17.

The shell 10 and the adapter 22 are constructed to make bayonet connection with each other and to that end the shell 10 is here shown as provided with a pair of bayonet slots 36, 37, each slot 30 having an axially extending portion 38 and a circumferentially extending portion 39, each circumferentially extending portion 39 also being formed to provide a bayonet seat 40. The adapter 22 is provided with a pair of diametrically opposite pins 41, 42 adapted to pass through the longitudinally extending portions 38 of the bayonet slots 36, 37, and, by turning of the adapter 22 to become seated in the bayonet seats 40.

The adapter 22 is also provided with a pair of 40 diametrically opposite bayonet slots 43, 44, each of the slots having a longitudinally extending portion 45 and a circumferentially extending portion 46, each circumferentially extending portion 46 being formed to provide a bayonet seat 45 47 for pins 48, 49 provided on a shell 50 constituting part of the lamp base 25. The diameter generally defining the diametrically opposite bayonet slots 43, 44 is in this instance at an angle to the diameter generally defining the pins 41, 50 52. The lamp base 25 is provided with a central contact 51 adapted to engage the left hand end of the conducting member 33.

The adapter 22 is here shown as further provided with a projection, in this instance a pin 55

52 fixed in a recess in and projecting a predetermined desired amount from the outer periphery of the adapter 22. The pin 52 is shown in Figures 1 and 2 disposed in the longitudinally 5 extending portion 38 of the bayonet slot 36 in the shell 10. The pin 52 is thus spaced circumferentially from the pin 41 a distance approximately equal to the circumferential distance of the bayonet seat 40 from the circumferential 10 center of the longitudinal portion 38 of the bayonet slot 36. The pin 52 is also shown as spaced axially from the pin 41. The left hand margin of the pin 52, as viewed in Figure 2, is shown as slightly beveled off to form a cam surface 53. 15 The right hand margin of the pin, as viewed in Figure 1, is also beveled off slightly to form a cam surface 54. Thus, as here shown, the pin has two cam surfaces at right angles to each other, one, the cam surface 53, adapted to function when the 20 adapter 22 is rotated and the other, the cam surface 54, adapted to function when the adapter 22 is moved longitudinally.

The connection means is assembled and operates as follows. Assuming that the insulating disc 12 with its attached conductor 15, the insulating disc 19, and the spring 21 have been assembled with the shell 10 as shown in Figure 1, the adapter 22 is inserted in the shell 10 with the pins 41, 42 in registry with the longitudinal 25 portions 38 of the bayonet slots 36, 37 in the shell 10. Continued inserting movement causes the right hand end of the conducting member 33 to engage the contact 17 thereby compressing the spring 21 until the cam surface 54 on the 30 pin 52 comes into engagement with the inner peripheral left hand terminal edge 55 of the shell. Further inserting movement causes the cam surface 54 to slightly flex the shell thereby permitting further entry of the adapter 22 into 35 the shell, the radially outer end of the pin 52 sliding longitudinally along the inner periphery of the shell 10. When the adapter 22 reaches the position in which the pins 41, 42 are circumferentially opposite the circumferential portions 40 39 of the bayonet slots 36, 37 the adapter may be turned about its axis to bring the pins 41, 42 45 onto the bayonet seats 40 of the bayonet slots 36, 37. Such turning movement causes the radially outer end of the pin 52 to slide off of 50 the inner periphery of the shell and brings the pin 52 into the longitudinal portion 38 of the bayonet slot 36. With the parts thus assembled, the spring 21 biases the insulating disc 12 toward the left, and hence biases the contact 17 55 against the right hand end of the conducting member 33, thereby biasing the flange 34 against the insulating disc 30 carried by the adapter 22. The pins 41, 42 of the adapter 22 are thus biased against the seats 40 of the bayonet slots 36, 37. 60 The base 25 of the lamp 26 may now be inserted in the cylindrical aperture 24 in the adapter 22, the contact 51 on the base engaging the left hand end of the conducting member 33 and moving the conducting member 33 against the bias of the spring 21 into the position shown in 65 Figure 1, in which the pins 48, 49 on the lamp base have been turned onto the bayonet seats 47 of the bayonet slots 43, 44 in the adapter 22.

In the position of the parts shown in Figure 1, 70 the flange 34 has been moved out of contact with the insulating disc 30, but now the pins 41, 42 of the adapter 22 are biased against the seats 40 of the bayonet slots 36, 37 by reason of the fact that the conducting member 33 biases the pins 75 48, 49 on the lamp base 25 against the seats 47

of the bayonet slots 43, 44 of the adapter 22 and therefore biases the adapter 22 toward the left as viewed in Figure 1.

It will of course be understood that, if desired, the lamp 26 may be assembled first with the adapter 22 and then the adapter 22 and lamp 26 assembled with the shell 10.

Assuming that the parts are in the position shown in Figure 1 and it is desired to remove the lamp 26 only, leaving the adapter 22 in the shell 10, the lamp 26 is pushed toward the right to unseat the pins 48, 49, and turned and withdrawn from the aperture 24 in the usual manner. Pushing the lamp toward the right to unseat the pins 48, 49, may also unseat from the seats 40 the pins 41, 42 of the adapter, and, in any event, will remove from the pins 41, 42 the biasing action of the spring 21. However, the pins 41, 42 are, under these conditions, maintained in axial alignment with the seats 40 by the pin 52, so that when the lamp 26 is removed the spring 21 will cause the flange 34 to engage the insulating disc 30, thus again biasing the pins 41, 42 of the adapter 22 against the seats 40.

Any counterclockwise turning movement of the adapter (as viewed in Figure 2) which may be produced merely by the movements necessary to remove the lamp 26 from the adapter is insufficient to overcome the resistance to turning of the adapter by reason of engagement of the cam surface 53 with the left hand side of the longitudinal portion 38 of the bayonet slot 36. For the foregoing reasons, removal of the lamp 26 leaves the adapter 22 in operative assembled position with the shell 10.

However, the adapter 22 may be removed from the shell 10 by pushing the adapter toward the right, as viewed in Figure 1, thereby unseating the pins 41, 42, and then turning the adapter 22 counterclockwise, as viewed in Figure 2, with sufficient turning moment to cause the cam surface 53 to flex the shell 10 so that the radially outer end of the pin 52 moves circumferentially in contact with the inner periphery of the shell 10. Such rotative movement of the adapter 22 is continued until the pins 41, 42 are in alignment with the longitudinal portion 38 of the bayonet slots 36, 37, whereupon the adapter 22 may be withdrawn from the shell 10.

It will be understood that where reference is made to flexing of the shell 10 by the pin 52, such flexing may be very slight while still accomplishing the desired results. Thus the shell 10 may be made of comparatively heavy stock and yet flex sufficiently to permit the hereinbefore described relative movements of the pin 52 to take place.

From the foregoing it will be apparent to those skilled in the art that the illustrated embodiment of my invention provides a new and improved electrical connection means, readily and conveniently constructed and assembled, and accordingly, accomplishes at least the principal object of my invention. On the other hand, it also will be obvious to those skilled in the art that the illustrated embodiment of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. In combination: socket means providing a socket of predetermined size; adapter means for

receiving electrical plug connection means of a size smaller than said predetermined size; a movable contact for said adapter means; bayonet connection means, having an element provided on 5 said socket means and an element provided on said adapter means, for connecting said adapter means and said socket means; and a single resilient means for biasing said bayonet connection elements into seated relation and for biasing 10 said movable contact.

2. In combination: socket means providing a socket; electrical plug connection means for reception in said socket means; bayonet connection means, having an element provided on said socket 15 means and an element provided on said plug connection means, for connecting said plug connection means and said socket means; holding means for releasably holding said bayonet connection means against unintentional unseating rotation; and said holding means comprising means for 20 causing flexure of said socket means upon unseating rotation.

3. In combination: socket means providing a socket; electrical plug connection means for reception in said socket means; bayonet connection means, having an element provided on said socket 25 means and an element provided on said plug connection means, for connecting said plug connection means and said socket means; holding means for holding said bayonet connection means against unseating rotation; and said holding means comprising means for causing flexure of 30 said socket means during assembly of said bayonet connection elements.

35 4. In combination: socket means providing a socket of predetermined size; adapter means, providing a socket, and having an element of a bayonet connection means; electrical plug connection means carrying a contact and being of a size smaller than said predetermined size, said 40 plug connection means being receivable by said adapter socket and having a bayonet connection element complementary to said socket element; a movable contact for said adapter means, said 45 movable contact being connectible to an electric source and being operable to contact said plug connection contact; bayonet connection means, having an element provided on said adapter means and an element provided on said socket 50 means, for connecting said adapter means and said socket means; and a single resilient means operable to urge said movable contact into engagement with the contact carried by said plug connection means, and thereby yieldably maintain 55 said connection means in cooperable relation with said adapter means and said adapter means in cooperable relation with said socket means.

5. In combination: socket means providing a 60 socket of predetermined size; adapter means for receiving an electrical plug connection means of a size smaller than said predetermined size, and having means cooperable with means carried by said connection means whereby a connection may be effected by relative movement between said 65 connection means and said adapter means; connection means whereby said adapter means may be connected to said socket means solely by relative movement of said two means; and means for holding said adapter means and said socket 70 means connected when said plug connection means is removed from said adapter means by relative movement.

6. In combination: socket means providing a 75 socket of predetermined size; adapter means for receiving an electrical plug connection of a size

smaller than said predetermined size, said plug being connectible to said adapter means by moving said plug relative to said adapter means; said adapter means being connectible to said socket means by moving said adapter means relative to said socket means; and means cooperable with said adapter means and said socket means so that a greater force is required to connect and disconnect said socket means and said adapter means than is required to connect and disconnect said 10 plug means and said adapter means.

7. In combination: socket means providing a socket of predetermined size; adapter means for receiving an electrical plug connection of a size smaller than said predetermined size; means 15 whereby said adapter means may be connected to said socket means solely by relative movement of said two means; and means for releasably holding said two means against unintentional releasing movement, said holding means being moved to latched position when said adapter means and said socket means are relatively moved to connected position.

8. In combination: socket means providing a socket; electrical plug connection means for reception in said socket means; bayonet connection means, including a bayonet slot element and a bayonet projection element, one element being provided on said socket, and the other element being provided on said plug connection means, said elements being cooperable to connect said plug connection means and said socket means; and a projection provided on the part carrying the bayonet projection, said projection being out of alignment with the axial part of said bayonet slot during initial connecting movement of said plug connection means and said socket means, but being disposed within the axial part of said bayonet slot after connection of said plug connection means and said socket means has been effected, said projection being engageable with the margins of the axial part of said bayonet slot to releasably hold said plug connection means and said socket means against unintentional releasing movement.

35 9. In combination: socket means providing a socket of predetermined size; adapter means, receivable within the socket of said socket means, and providing a socket of a size smaller than said predetermined size; means carried by said adapter means and said socket means, constructed and arranged so that said adapter means and said socket means are connectible and disconnectible by relative movement; plug means receivable within the socket of said adapter means; means carried by said plug means and said adapter means, constructed and arranged so that said plug means and said adapter means are connectible and disconnectible by relative movement; and means constructed and arranged with respect to the aforementioned connection means, so that a greater force is required to connect and disconnect said socket means and said adapter means than is required to connect and disconnect said plug means and said adapter means.

60 10. In combination: socket means providing a socket of predetermined size; movable contact means associated with said socket means; adapter means for receiving electrical plug connection means of a size smaller than said predetermined size; movable contact means associated with said adapter means, and being adapted to electrically engage said socket contact means; bayonet connection means, in part carried by said socket means, and in part carried by said adapter 65 means.

means, said parts being constructed and arranged to connect said adapter means and said socket means; and a single resilient means, constructed and arranged to urge said socket contact means and said adapter contact means to electrical engagement when said adapter means and said socket means are connected.

11. In combination: socket means having a resilient defining wall, and providing a socket of a predetermined size; adapter means for receiving an electrical plug connection of a size smaller than said predetermined size; and holding means, whereby said adapter and socket means may be connected together solely by relative movement, 15 said holding means including, seats provided in said socket means, and a plurality of projection means provided on said adapter means, at least one of said projection means being constructed and arranged to engage and cause expansion of 20 said resilient defining wall during a certain period of connection of said socket means and said adapter means, and during the final period of connection said one projection means disengaging said defining wall causing resilient contraction 25 of said defining wall from its expanded relation

to a position in said seats with a snap action.

12. In combination: socket means having a resilient expandible and contractible defining wall providing a socket of a predetermined size; adapter means for receiving an electrical plug connection of a size smaller than said predetermined size; holding means whereby said adapter and socket means may be connected together solely by relative movement, said holding means including, bayonet slots leading to seats in said socket means, and bayonet pins and cam means on said adapter means; said cam means, when said adapter means is moved into connecting relation with said socket means, being constructed 15 and arranged to engage and expand said resilient defining wall during a certain period of relative connecting movement, and to disengage and cause contraction of said resilient defining wall during final relative connecting movement so as 20 to urge said cam means into at least one of said bayonet slots at the same time said bayonet pins are moved to a position in said seats.

HARRY A. DOUGLAS. 25
